UNITED STATES PATENT OFFICE.

JOHN F. G. FERGUSON, OF BOWIE, TEXAS.

DESIGN FOR A KITCHEN-CABINET.

SPECIFICATION forming part of Design No. 27,670, dated September 21, 1897.

Application filed August 9, 1897. Serial No. 647,639. Term of patent 14 years.

To all whom it may concern:

Be it known that I, JOHN F. G. FERGUSON, a citizen of the United States, residing at Bowie, in the county of Montague and State 5 of Texas, have invented a new and original Design for Kitchen-Cabinets, of which the following is a specification.

This invention relates to a new and original design for kitchen-cabinets; and it has for 10 its object to provide a design of this character that shall be both useful and ornamental.

The leading feature of the design resides in a rectangular upright body having a framework of strips provided with longitudinal 15 beads or ribs and a horizontal flat rectangular top board, said body being further provided in the front side thereof with oppositely-located large rectangular openings having beveled edges and plain flat bin-panels 20 therein, and between said oppositely-located rectangular openings with a central rectangular panel portion having beveled edges, a central vertical dividing-strip extending downward from the upper edge of said panel 25 portion, and a horizontal panel-dividing strip or stile at the lower end of said vertical strip, a pair of square drawer-panels arranged within said central panel portion of each side of the vertical dividing-strip and provided with 30 circular beveled recesses, and circular projections disposed concentrically within said recesses, and a single wide rectangular drawer-panel arranged within said central panel portion immediately below the horizontal panel- 35 dividing strip or stile.

A minor feature of the design resides in providing the rectangular body at each end with a plain sunken panel-board surrounded by a step series of rectangular beveled frames.

40 In the drawings, Figure 1 is a perspective view of a kitchen-cabinet embodying the herein-described design. Fig. 2 is a front elevation thereof. Fig. 3 is an end view thereof.

Referring to the accompanying drawings, 45 the numeral 1 designates the rectangular upright body of the cabinet, having at the front side and ends thereof the upper and lower horizontal frame-strips 2 and 3, respectively, and the vertical corner-posts 4, connecting said 50 upper and lower frame-strips, said upright

body also having at the front side thereof a pair of vertical panel-strips 5, connecting the upper and lower frame-strips, all of said strips 2, 3, 4, and 5 being provided on their front exposed faces with longitudinal rounded beads 55 or ribs 6. The front vertical panel-strips 5, in connection with the front pair of corner-posts, form at the front side of the upright body of the cabinet the oppositely-located rectangular openings 7, having surrounding 60 beveled edges 8 and receiving therein the plain flat rectangular bin-panels 9. Between the pair of front vertical panel-strips 5 the body 1 is further provided with a central rectangular panel portion 10, having surrounding beveled edges 11, a central vertical dividing-strip 12, projecting downwardly from the top of the panel 10, and a horizontal panel-dividing strip or stile 13, arranged at the lower end of the strip 12 and connecting the 70 strips 5, said strips 12 and 13 being provided on their front exposed faces with longitudinal rounded beads or ribs. A pair of squared drawer-panels 14 are arranged within the panel portion 10 at each side of the vertical 75 strip 12 and are provided with circular beveled recesses 15 and circular projections 16, disposed concentrically within said recesses. Immediately below the horizontal panel-dividing strip or stile 13 is arranged a single 80 wide rectangular drawer-panel 17, which is provided with knob projections 18 and above and below said knob projections with horizontal longitudinally-extending sunken beaded work 19.

85 The design is completed by providing each end of the body 1 with a plain sunken panel-board 20, surrounded by a step series of rectangular beveled frames 21.

90 What I claim is—

The design for a kitchen-cabinet, herein shown and described.

In testimony that I claim the foregoing as my own I have hereto affixed my signature in the presence of two witnesses.

JOHN F. G. FERGUSON.
